UNITED STATES PATENT OFFICE.

EDMUND R. RAYBURN, OF FINDLAY, OHIO.

DESIGN FOR A HOT PLATE.

Application filed January 31, 1927. Serial No. 20,555. Term of patent 7 years.

To all whom it may concern:

Be it known that I, EDMUND R. RAYBURN, a citizen of the United States, residing at 512 Howard St., Findlay, Ohio, have invented a new, original, and ornamental Design for a Hot Plate, of which the following is a specification, reference being had to the accompanying drawing, forming a part thereof.

Fig. 1 is a plan view of a hot plate showing my new design;

Fig. 2 is an elevation thereof.

I claim:

The ornamental design for a hot plate as shown.

EDMUND R. RAYBURN.
